PHASE AND FREQUENCY MODULATION
RECEIVERBertram Trevor, Riverhead, N. Y., assignor to
Radio Corporation of America, a corporation of
Delaware

Application November 13, 1941, Serial No. 418,927

12 Claims. (Cl. 250—20)

My present invention relates to receiving systems adapted to receive phase or frequency modulated carrier waves, and more especially to improvements in the discriminator, detector, and audio frequency circuits of ultra-high frequency control and relay receivers employed in phase modulated carrier wave reception.

There has been disclosed by G. Mountjoy in application Serial No. 345,903, filed July 17, 1940, granted April 21, 1942, as U. S. Patent No. 2,280,536, a discriminator-detector circuit for phase or frequency modulated carrier waves. In that detector circuit the signal input circuits of the rectifiers are oppositely and equally mistuned from the center frequency of the applied modulated waves, and symmetry is provided in the detection characteristics by utilizing mutual inductance between the input circuits to cancel the effects of any capacitance coupling thereto from prior networks.

It is one of the main objects of my present invention to provide in a receiver of angular velocity-modulated carrier waves, a detector of the type disclosed in the aforesaid Mountjoy patent which is further improved so that a perfectly balanced discriminator is had for all frequencies of modulation.

Another important object of my present invention is to provide in an ultra-high frequency receiving system for phase modulated carrier waves, a perfectly balanced discriminator-detector network which includes novel modulation voltage coupling networks subsequent to the detector in order to eliminate undesirable effects caused by the presence of amplitude modulation components which may be passed by an imperfect limiter.

Still another object of the invention may be stated to reside in the provision of a relatively wide band phase or frequency modulation receiver, such as may be employed for facsimile, television or multiplex communication, and wherein there is utilized a discriminator-detector network of the type disclosed in the aforesaid Mountjoy patent, but which detector terminates in a network functioning to produce a flat modulation voltage response over the entire modulation frequency spectrum.

Still other objects of my invention may be stated to reside in the provision of improved discriminator and audio frequency circuits for ultra-high frequency control and relay receivers utilized for phase modulation reception, and particularly in circuits which are economically and easily manufactured and assembled.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:

Fig. 1 shows only that portion of a receiving system embodying my present invention,

Fig. 2 shows a modification.

Referring now to the accompanying drawing, wherein like reference characters in the two figures designate similar circuit elements, by way of illustration it is pointed out that the receiving system shown in Fig. 1 is embodied in an ultra-high frequency control and relay receiver utilized for phase modulation reception. Only such of the networks of such a receiving system are shown as is necessary to a proper understanding of the present invention. The receiving system is of the superheterodyne type, and employs an operating intermediate frequency (I. F.) of, for example, 8 megacycles (mc.). The I. F. band width is wide, and may be of the order of 200 kilocycles (kc.).

The networks preceding the I. F. network have not been shown, since those skilled in the art are fully acquainted with the manner of collecting the radiated ultra-high frequency modulated carrier waves. They are also fully aware of the means that can be used to convert the ultra-high frequency modulated waves to the modulated carrier waves whose center frequency (F_c) is of the operating I. F. value. The radiated ultra-high frequency waves may have a center frequency of between 100 and 500 mc. if desired.

The I. F. energy output of the converter may be transmitted through as many I. F. amplifier stages as is desired. To preserve simplicity of disclosure, there is shown in Fig. 1 but a single I. F. amplifier tube 1. The signal input grid of the latter is connected to the high potential side of the resonant input circuit 2 which is shunted by the damping resistor 3. The circuit 4, shunted by damping resistor 5, is magnetically coupled to the input circuit 2, and each of the circuits 4 and 2 is resonated to the operating I. F. value. The entire network 5—4—2—3 has a band pass characteristic whose pass band is 200 kc. wide, so that the modulated carrier wave may be transmitted to the amplifier 1 with sub-

stantial uniformity. The I. F. amplifier tube 1 is of the usual and well known construction, and its plate circuit is provided with a resonant output circuit 6 which is tuned to the I. F. value. The circuit 6 is magnetically coupled to the following resonant circuit 7.

Here, again, the network 6-7 is constructed as a band pass network whose pass band width is 200 kc. wide. The circuit 7 feeds its modulated carrier wave energy into a limiter tube 8. The limiter may be constructed in any well known manner, and may include the grid condenser 9 and leak resistor 10 whose constants are chosen to provide amplitude modulation limiting action. Those skilled in the art are fully aware of the manner of functioning of the limiter, and realize that it acts to eliminate most of the amplitude modulation effects existing on the carrier. These effects may arise due to noise impulses, fading or even because of the passage of the waves through the various cascaded resonant circuits up to the limiter tube. The voltages of the various cold electrodes of the limiter tube 8 are chosen so as to render tube 8 a readily-saturated amplifier whose output amplitude above a predetermined level is substantially flat.

Automatic volume control (AVC) may be provided so as to improve the action at the limiter stage, as well as to compensate for carrier fading at the signal collector. This is easily accomplished in any well known manner, and in Fig. 1 there is shown one method of securing AVC bias for the control grids of the ultra-high frequency amplifiers or I. F. amplifiers which are to be controlled in gain. A diode 11 may have its anode connected to the high potential side of the limiter input circuit 7, while the cathode of diode 11 is connected through condenser 12 to the low potential side of input circuit 7.

The low potential terminal of the coil of input circuit 7 may be connected to a source of negative voltage so that the diode 11 and associated load circuit 14, 13 is maintained at a substantial negative potential in order to cooperate properly with the direct current amplifier 15, which supplies the control potentials to the controlled tubes. The numeral 13 designates the load resistor of the diode 11, and numeral 14 designates a filter network which prevents I. F. energy from being fed to the load resistor 13 or D. C. amplifier 15. The voltage tapped off from the cathode end of resistor 13 may be applied to the direct current voltage amplifier 15 of any desired construction, and the amplified AVC bias may then be applied to the grids of the controlled amplifiers. Of course, the amplifier 15 functions to reverse the polarity of the direct current voltage at the positive end of resistor 13 so that it is readily applied to the signal control grids of the controlled amplifiers.

The discriminator-detector network comprises a pair of resonant circuits F₂ and F₁ arranged in series in the plate circuit of the limiter tube 8. The proper positive voltage is applied to the plate of limiter 8 through the coils 16 and 17 of the series tuned circuits. The coils 16 and 17 are magnetically coupled, as indicated by M. The low potential end of coil 17 is by-passed to ground by condenser 18. The diode 19 is operatively associated with tuned circuit F₂, while diode 20 is associated with the tuned circuit F₁. The resistor 21 functions as the load resistor for diode 19 and is connected in shunt therewith, while resistor 22 is the load resistor for diode 20 and shunts the latter.

Resistors 21 and 22 are arranged in series, and the junction thereof is connected to the cathodes of diodes 19 and 20 which are themselves connected in common. The junction of resistors 21 and 22 is connected to the junction of coils 16 and 17 through the balancing condenser 23. The balancing condenser 24 connects the high potential end of coil 16 to the anode end of resistor 21, while a third balancing condenser 25 connects the anode end of resistor 22 to ground. The input circuits F₁ and F₂ are oppositely mistuned with respect to the center frequency F_c. That is, tuned circuit F₂ will be tuned to one side of the operating I. F. value, say a frequency spacing of 0.1 mc. The input circuit F₁ would then be mistuned to the opposite side of F_c by the same 0.1 mc. amount.

As disclosed in the aforesaid Mountjoy patent, there is an inherent circuit capacity coupled between the prior networks and the detector input circuits. Such capacity is due to the plate to ground capacity of the limiter tube plus the attendant plate winding and circuit capacitance to ground. This inherent capacity tends to render the detection characteristic unsymmetrical. Proper poling and adjustment of M, the mutual inductance between coils 16 and 17, will cancel out the effect of the undesired inherent capacity, and a symmetrical detection characteristic results. These series circuits are tied directly across the limiter plate circuit.

The maximum rectified voltage appears across resistor 21 when the instantaneous frequency of the modulated carrier energy is substantially that of the circuit F₂. Similarly, maximum rectified voltage appears across resistor 22 when the modulated carrier energy frequency is equal to the resonant frequency of circuit F₁. Between these two frequencies of the frequency modulated carrier the rectified voltage across each of load resistors 21 and 22 will depend upon the frequency displacement of the instantaneous carrier frequency with respect to the resonant frequencies of each of the input circuits F₂ and F₁. If the low potential end of resistor 22 were directly grounded, as shown in Fig. 2, the effective output voltage at the upper end of resistor 21 would depend upon the difference between the rectified voltages produced across resistors 21 and 22.

However, in Fig. 1 the input grids of a push-pull audio amplifier are driven from the opposite ends of load resistors 21 and 22, and, therefore, it will be seen that the detector output load in Fig. 1 is arranged for push-pull audio operation. Since the audio frequency voltage components are represented by frequency deviations of the carrier, it will be seen that the voltage taken off at the opposite ends of resistors 21 and 22 is the audio modulation voltage. As is well known to those skilled in the art, in phase modulation a relatively greater increase of frequency deviation of the carrier occurs at the upper audio frequencies compared with the deviation at low audio frequencies. That is, the upper audio frequencies are emphasized by producing a relatively wider frequency deviation of the carrier. Hence, a correction network is usually employed in the output of the detector network where phase modulated waves are received. Such a correction network de-emphasizes the higher audio frequencies so that there is secured a flat audio response over the audio frequency spectrum. In the absence of such a correction network the output of the detector would rise with frequency when phase modulated carrier waves are received.

The audio amplifier tubes 30 and 30' have their cathodes connected in common, and the common cathodes are connected to ground through a resistor 35. The grid of tube 30 is connected to the anode of diode 19 through a path which includes condenser 31 and resistor 32 arranged in series, the junction of condenser 31 and resistor 32 being connected to ground through a condenser 33. Similarly the grid of tube 30' is connected to the anode of diode 20 through a path which includes condenser 31' and resistor 32' arranged in series, the junction of the latter two elements being connected to ground through condenser 33'. Condensers 33 and 33' with their associated resistors 32 and 32' provide the correction network referred to above. Furthermore, the anode of diode 19 is connected to the anode of diode 20 through a pair of series resistors 34 and 34' whose junction is grounded. Automatic frequency control (AFC) voltages may be taken off from the opposite ends of the load resistors 21 and 22.

This is accomplished by connecting the junction of resistor 32 and condenser 31 to ground through a path which includes resistor 40 and condenser 41 in series. The junction of resistor 40 and condenser 41 is connected to one AFC bias lead. Similarly, a second AFC bias lead is connected to the junction of resistor 40' and condenser 41' arranged in series between the junction of resistor 32' and condenser 31' and ground. The potentials on these AFC leads control a balanced D. C. amplifier which in turn controls the frequency of the local oscillator employed in connection with the first, or second, detector as the case may be. Briefly, the AFC network acts to correct the local oscillator frequency in a sense to maintain the operating I. F. value. A push-pull AFC system of the type that can be used in the present case is shown in my U. S. Patent 2,241,937.

A perfectly balanced discriminator is had for all frequencies of demodulation if the three capacitances 24, 23, 25 are made equal, and have high reactances compared with resistors 21, 22 for all modulation frequencies used. In that case any amplitude modulation components which are passed by the limiter are perfectly balanced out, and do not appear in the output of the audio frequency network. Perfect balance is obtained only if the values of the capacities of condensers 24, 23, and 25 are equal as well as the corresponding resistors and condensers (referred to with numerals and corresponding primes) in the coupling network between the diodes 19 and 20 and the audio amplifier tubes 30 and 30'.

The audio amplifier tube 50 is supplied from the plate circuit of tube 51. The plate of tube 51 is connected to the plate of tube 30, the positive plate voltage being supplied to these plates through resistor 52. The plate of tube 30' is connected to the positive voltage source through a resistor. The plate of tube 30' is connected to ground through a series path comprising condenser 54, condenser 55 and resistor 56. The condenser 55 is shunted by resistor 57. The adjustable tap 58 is slideable along potentiometer resistor 56. Tap 58 is connected to the control grid of tube 51. The direct current voltage developed across bias resistor 35, the latter being shunted by a bypass condenser, is used to provide bias for the grids of tubes 30, 30' and 51.

The grid of tube 50 is connected to the adjustable tap 60 of potentiometer resistor 61. The lat-

ter has its lower end grounded, while its upper end is coupled by condenser 62 to the plate of tube 51. The tube 50 has a self-biasing resistor 63 in its cathode circuit. The audio voltage developed across the plate load resistor 70 is transmitted to the succeeding audio utilization network.

In the connection between condenser 31' and the junction of resistors 32'-40' there is located a switch arm 80 which is adjustable between contacts P and B. The contact B is connected by lead 81 to the left terminal of condenser 31. Normal angular modulation components appear push-pull between the grids of tubes 30 and 30' when the switch arm 80 is on contact P (operation connection). The "balance" potentiometer 56-58 is adjusted to feed the grid of tube 51 with exactly the same voltage that appears at the grid of tube 30. Due to the 180 degree phase reversal at tube 30', the voltages on the grids of tubes 30 and 51 are in phase and are equal in magnitude. Therefore, tubes 30 and 51 operate effectively in parallel to drive the control grid of tube 50 through the "gain" potentiometer 60-61.

Should any undesired amplitude modulation components pass through the limiter, a push-push input is applied to the grids of tubes 30 and 30'. It will now be seen that the voltages on the control grids of tubes 30 and 51 are equal in magnitude but opposite in phase. This is the condition for perfect balance, since no amplitude modulation input reaches the grid of tube 51. This effectively eliminates unwanted amplitude modulation components if the discriminator is well balanced in the manner described above. The purpose of switch 80 is to permit an accurate adjustment of the "balance" potentiometer 58. This adjustment is made by throwing the switch in the "B" position which ties the grids of tubes 30 and 30' in parallel. The potentiometer 58 is then adjusted for zero output of tube 50 with normal input to tubes 30-30'.

In Fig. 2 there is shown the manner in which the demodulator output load is arranged for feeding a single audio channel as disclosed in the said Mountjoy patent. The correction network comprises resistor 90 arranged in series with condenser 91, and the series path is connected in shunt across the two series-arranged diodes 19 and 20. The AFC bias may be taken off from the junction of resistor 90 and condenser 91. The resistor-condenser filter 92 functions to filter out any pulsation voltage components in the AFC bias. The audio voltage is taken off from the junction of resistor 90 and condenser 91, and is transmitted through condenser 93 to the control grid of audio amplifier 93. A proper bias may be applied to the control grid 93 through a resistor 94, and the cathode of tube 93 is connected to ground through a load resistor 95. Audio voltage for the following audio frequency network may be taken off in any desired magnitude by means of the adjustable tap 96 which is slideable along resistor 95.

The advantage of the present invention is best appreciated by comparison of the arrangement of Fig. 1 with that shown in Fig. 2.

First, it should be pointed out that the single ended arrangement shown in Fig. 2 does not provide a substantially perfect balance against AM components passing an imperfect limiter at the higher audio frequencies where appreciable audio frequency current flows through the capacitors 23 and 24. In this circuit amplitude modulation components passing the limiter pro-

duce equal and opposite voltages across resistors 21 and 22, assuming these two resistors have equal values of resistance. Then if no appreciable audio frequency current flows through the capacitors 23 and 24, we have a balanced condition which gives no audio output for the AM components. As soon as the audio frequency becomes high enough (for example, 100 kc.) considerable current will flow through capacitors 24 and 23, upsetting the balance which allows AM components to pass into the audio system.

To go back to the circuit of Fig. 1, I have overcome this difficulty by arranging the discriminator output push-pull. This is accomplished by adding the capacitor 25 and the balanced voltage divider 34, 34' which grounds the midpoint of the discriminator output for both direct current and alternating current potentials. The capacitors 31 and 31' are merely coupling capacitors to the grids of tubes 30 and 30' respectively. If, now, we have AM components passing the limiter, we again have equal and opposite voltages developed across the resistors 21 and 22. If the three capacitors 23, 24, 25 are equal in reactance, any audio frequency current flowing in them does not disturb the balance, but we do get a push-push input to the audio frequency amplifier which is so balanced that it will not respond to this type of input.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In a receiver of phase modulated carrier waves, a limiter tube provided with input and output electrodes, a discriminator-detector network following the limiter, said network comprising a diode rectifier circuit provided with a resonant input circuit and a resistive output load, a second diode rectifier circuit provided with a second resonant input circuit and a second resistive output load, means connecting said resistive loads in phase opposition, said input circuits being oppositely and equally mistuned relatively to the center frequency of said waves and arranged in series relation with each other and in series with the space discharge paths of said rectifier diodes, said resistive loads being connected in series between the anodes of said diodes, said loads being connected directly in shunt with said series arranged input circuits, a condenser connecting the junction of the resistive loads to the junction of said input circuits, a second condenser connecting the anode end of one resistive load to that side of the input circuit associated therewith, a third condenser between the anode end of the second resistive load and that side of the input circuit associated therewith, said three condensers being of equal value, a resistive path in shunt with said diodes, the midpoint of said last path being grounded, and a balanced push-pull audio amplifier coupled to said resistive path, thereby to provide a perfect balance for amplitude modulation components.

2. In a receiver of phase modulated carrier waves, a limiter tube provided with input and output electrodes, a discriminator-detector network following the limiter, said network comprising a diode rectifier circuit provided with a resonant input circuit and a resistive output load,

a second diode rectifier circuit provided with a second resonant input circuit and a second resistive output load, means connecting said resistive loads in phase opposition, said input circuits being oppositely and equally mistuned relatively to the center frequency of said waves and arranged in series relation with each other and in series with the space discharge paths of said rectifier diodes, said resistive loads being connected in series between the anodes of said diodes, said loads being connected directly in shunt with said series arranged input circuits, a condenser connecting the junction of the resistive loads to the junction of said input circuits, a second condenser connecting the anode end of one resistive load to that side of the input circuit associated therewith, a third condenser between the anode end of the second resistive load and that side of the input circuit associated therewith, said three condensers being of equal value, a separate correction network connected in shunt across each of said diodes to provide a flat audio response over the audio frequency spectrum, and a balanced push-pull audio amplifier, coupled to said correction networks, which is unresponsive to push-push input voltages.

3. In combination with a demodulator for angular-velocity modulated carrier waves of the type wherein a plurality of different types of modulation exist on a common carrier, a demodulator comprising a pair of opposed rectifiers having separate input circuits and load resistors, said input circuits being equally and oppositely mistuned relative to the center frequency of the modulated carrier waves, a push-pull amplifier having its input electrodes connected to the opposed diodes to derive modulation voltage from said resistive loads, an inverter stage to convert the push-pull amplifier to a single-ended one, said inverter stage including an electron discharge tube whose plate is connected in parallel with the plate of one of the push-pull amplifier tubes and whose input grid is cross-connected to the plate of the opposite one of said push-pull amplifier tubes and a balancing potentiometer connected between the inverter grid and the last named plate.

4. In a phase modulation receiver, a limited tube provided with input and output electrodes, a discriminator-detector network following the limiter, said network comprising a diode rectifier circuit provided with a resonant input circuit and a resistive output load, a second diode rectifier circuit provided with a second resonant input circuit and a second resistive output load, means connecting said resistive loads in phase opposition, said input circuits being in series relation and oppositely and equally mistuned relatively to the center frequency of said waves, a condenser connecting the junction of the resistive loads to the junction of said input circuits, a second condenser connecting the anode end of one resistive load to that side of the input circuit associated therewith, a third condenser between the anode end of the second resistive load and that side of the input circuit associated therewith, said three condensers being of equal value, a pair of symmetrical correction circuits connected to said diodes, and a pair of series-arranged balancing resistors connected across said diodes.

5. In combination, a limiter tube provided with input and output electrodes, a detector network following the limiter, said network comprising a diode rectifier circuit provided with a resonant

input circuit and a resistive output load, a second diode rectifier circuit provided with a second resonant input circuit and a second resistive output load, means connecting said resistive loads in phase opposition, said input circuits being series-related and oppositely and equally mistuned relative to the center frequency of said waves, a condenser connecting the junction of the resistive loads to the junction of said input circuits, a second condenser connecting the anode end of one resistive load to that side of the input circuit associated therewith, a third condenser between the anode end of the second resistive load and that side of the input circuit associated therewith, a balanced push-pull amplifier, unresponsive to push-push input voltages, connected to said diodes, and a phase inverter connected to said balanced amplifier to provide a single-ended amplifier circuit.

6. In combination with a demodulator for angular-velocity modulated carrier waves of the type wherein a plurality of different types of modulation exist on a common carrier, a demodulator comprising a pair of opposed rectifiers having separate input circuits and load resistors, said input circuits being equally and oppositely mistuned relative to the center frequency of the modulated carrier waves, a balanced push-pull amplifier having its input electrodes connected to the opposed diodes to derive angular modulation voltage from said resistive loads, an inverter stage coupling an angular modulation channel to the output of said push-pull amplifier, said inverter stage including a tube whose plate is connected to the plate of a given one of the push-pull amplifier tubes and whose input grid is cross-connected to the plate of the opposite one of said push-pull amplifier tubes, means for selectively connecting the grids of the push-pull amplifier in common, and a balance potentiometer connecting the inverter input grid to the last named plate.

7. In combination with a demodulator for phase modulated carrier waves of the type wherein a demodulator comprises a pair of opposed rectifiers having separate input circuits and load resistors, said input circuits being equally and oppositely mistuned relative to the center frequency of the modulated carrier waves, a push-pull amplifier having its input electrodes connected to the opposed diodes to derive the phase modulation voltage from said resistive loads, means for selectively connecting the push-pull amplifier input electrodes to a common point of said load resistors, a phase modulation voltage utilization channel, an inverter stage coupling said channel to the output of said push-pull amplifier, and a pair of symmetrical correction circuits connected between said diodes and the push-pull amplifier input electrodes.

8. In combination with a discriminator-detector network for phase modulated carrier waves comprising a diode rectifier circuit provided with a resonant input circuit and a resistive output load, a second diode rectifier circuit provided with a second resonant input circuit and a second resistive output load, means connecting said resistive loads in phase opposition, said input circuits being oppositely and equally mistuned relatively to the center frequency of said waves and arranged in series relation with each other and in series with the space discharge paths of said rectifier diodes, said resistive loads being connected in series between the anodes of said diodes, said loads being connected directly in shunt

with said series arranged input circuits; the improvement comprising a condenser connecting the junction of the resistive loads to the junction of said input circuits, a second condenser connecting the anode end of one resistive load to that side of the input circuit associated therewith, a third condenser between the anode end of the second resistive load and that side of the input circuit associated therewith, said three condensers being of equal value, a resistive path in shunt with said diodes, and the midpoint of said last path being grounded.

9. In a discriminator-detector network for phase modulated carrier waves, a diode rectifier circuit provided with a resonant input circuit and a resistive output load, a second diode rectifier circuit provided with a second resonant input circuit and a second resistive output load, means connecting said resistive loads in phase opposition, said input circuits being oppositely and equally mistuned relatively to the center frequency of said waves and arranged in series relation with each other and in series with the space discharge paths of said rectifier diodes, said resistive loads being connected in series between the anodes of said diodes, said loads being connected directly in shunt with said series arranged input circuits, a condenser connecting the junction of the resistive loads to the junction of said input circuits, a second condenser connecting the anode end of one resistive load to that side of the input circuit associated therewith, a third condenser between the anode end of the second resistive load and that side of the input circuit associated therewith, said three condensers being of substantially equal value, and a separate correction network connected in shunt across each of said diodes to provide a flat audio response over the audio frequency spectrum.

10. In combination with a demodulator for angular-velocity modulated carrier waves of the type wherein a plurality of different types of modulation exist on a common carrier, a demodulator comprising a pair of opposed rectifiers having separate input circuits and load resistors, said input circuits being equally and oppositely mistuned relative to the center frequency of the modulated carrier waves, a push-pull amplifier having its input electrodes connected to the opposed diodes to derive modulation voltage from said resistive loads, means for selectively connecting said input electrodes to a common point of said load resistors, an inverter stage to convert the push-pull amplifier to a single-ended one, said inverter stage including an electron discharge tube whose plate is connected in parallel with the plate of one of the push-pull amplifier tubes and whose input grid is adjustably cross-connected to the plate of the opposite one of said push-pull amplifier tubes.

11. In a discriminator-detector network for angular velocity modulated carrier waves, a diode rectifier circuit provided with a resonant input circuit and a resistive output load, a second diode rectifier circuit provided with a second resonant input circuit and a second resistive output load, means connecting said resistive loads in phase opposition, said input circuits being in series-relation and oppositely and equally mistuned relatively to the center frequency of said waves, a condenser connecting the junction of the resistive loads to the junction of said input circuits, a second condenser connecting the anode end of one resistive load to that side of the input circuit associated therewith, a third con-

denser between the anode end of the second resistive load and that side of the input circuit associated therewith, and a pair of series-arranged balancing resistors connected across said diodes.

12. In combination, a diode rectifier circuit provided with a resonant input circuit and a resistive output load, a second diode rectifier circuit provided with a second resonant input circuit and a second resistive output load, means connecting said resistive loads in phase opposition, said input circuits being series-related and oppositely and equally mistuned relative to the

center frequency of applied frequency-variable waves, a condenser connecting the junction of the resistive loads to the junction of said input circuits, a second condenser connecting the anode end of one resistive load to that side of the input circuit associated therewith, a third condenser between the anode end of the second resistive load and that side of the input circuit associated therewith, and a balanced push-pull amplifier, unresponsive to push-push input voltages, connected to said diodes.

BERTRAM TREVOR.
